UNITED STATES PATENT OFFICE

ADOLPH MUELLERWEISS, OF SEBEWAING, MICHIGAN

ATTACHMENT PLUG RECEPTACLE

Application filed March 2, 1929. Serial No. 343,857.

This invention relates to receptacles, and more particularly to electrical receptacles in which a pronged plug-cap is adapted to be inserted.

The prime object of the invention is to so shape and form the top of the receptacle, so that it acts as a guide for guiding the plug blades into the slots.

Another object is to provide a receptacle plug having a flat depressed surface, the marginal edges of which are shouldered to the end that the plug can be quickly and easily connected, even in the dark.

A further object is to so design and shape the face of the receptacle, so that the prongs of any standard plug naturally move into alinement and register with the slots, which is simple and inexpensive to manufacture, which facilitates the connection of the plug and which in no manner changes the operation thereof.

With the above and other objects in view, the present invention consists in the combination and arrangement of parts, herein-after more fully described, and illustrated in the accompanying drawings, and particularly pointed out in the appended claims, it being understood that changes may be made in the form, size, proportion, and minor details of construction, without departing from the spirit, or sacrificing any of the advantages of the invention.

In the drawings:

Fig. 1 is a top plan view of a receptacle having tandem blades or prongs.

Fig. 2 is a part sectional side view thereof, also showing a plug in combination therewith.

Fig. 3 is also a plan view of a receptacle having parallel blades or prongs.

Fig. 4 is a similar view of a receptacle of the combination type, designed to receive either tandem or parallel prongs.

Fig. 5 is a part sectional side view thereof.

Fig. 6 is a plan view of a receptacle such as used for pronged radio tubes.

Receptacles such as are on the market at the present time are formed with a substantially flat upper surface having spaced apart prong receiving openings therein, and which

are adapted to receive the prongs of a conventional plug. In flush wall and floor sockets, electrical appliances and radios, and in fact in any place where receptacles of this design are used, it is quite difficult to insert the 55 prongs, due to smooth upper surface of the receptacle, and the fact that the receptacle is generally in a position where a good view cannot be obtained, consequently the prongs of the plug must be slid and moved around 60 until they register in the proper manner, this is generally very inconvenient, because the person doing the connecting must bend to an awkward position, oftentimes the light is very 65 dim or it may be entirely dark, and this groping endeavoring to make the plug connecting is not conducive to the improvement of one's disposition, and I have therefore perfected a receptacle in which the aforesaid disadvantages are eliminated, and in which the prongs 70 are naturally guided into place.

Referring now particularly to the drawings, the numeral 5 indicates a receptacle having a screw shell body portion 6 for securing it in a socket, spaced apart openings 7 being provided in the face, and are adapted 75 to receive the prongs 8 of a plug member 9 in the usual manner.

The top of the receptacle is formed with a flat depressed portion 10, terminating in a sharply defined shoulder 11, certain edges of each of the openings, remote from said flat depressed portion, being in direct vertical alinement with said shoulder with the exception of the receptacle 12 which is designed 80 for radio tubes, and which is formed with a plurality of prongs which register with the openings 13.

In Figs. 4 and 5 of the drawings I have 85 shown a combination receptacle which can be used with a plug having either tandem or parallel prongs, in this construction the centrally disposed heart shaped raised surface 14 projects beyond the prong openings, and it will be clearly obvious that by placing the 90 prongs of a plug on the depressed surface, and moving towards the center of the receptacle, that the plug will automatically 95 turn, (if necessary) and register with the opening in the face of the receptacle, as the

shoulder follows the round outer edge of the plug, and thence leads to the openings, so that the prongs naturally assume the proper position. With my improved construction the 5 plug can be quickly and readily inserted in the dark, or without looking at the receptacle, as the prongs are naturally guided to proper position, and there is no possibility of inserting one of the prongs in the wrong opening.

19 From the foregoing description it will be obvious that I have perfected a very simple, inexpensive, and convenient receptacle.

What I claim is:

15 1. In a separable attachment plug, guide means incorporated in the top face of the base for directing prongs into register with separate openings therein, said guide means consisting of forming said top face of the base into two surfaces separated by an abrupt 20 shoulder that extends directly across from one to another of said openings flush with a wall of each.

25 2. In a separable attachment plug, guide means incorporated in the top face of the base for directing prongs into register with separate openings therein, said guide means consisting of forming said top face of the base into two surfaces separated by an abrupt shoulder that extends directly across from 30 one to another of said openings flush with a wall of each, said shoulder also extending beyond said openings in the manner of an endless enclosure encompassing said openings.

35 3. In a separable attachment plug, guide means incorporated in the top face of the base for directing the prongs into register with separate openings therein, said guide means consisting of forming said top face of the 40 base into two surfaces separated by an abrupt shoulder that extends from one to another of said openings flush with a wall of each, said shoulder also extending beyond said 45 openings in the manner of an endless enclosure encompassing said openings.

In testimony whereof I hereunto affix my signature.

ADOLPH MUELLERWEISS.
